X-RAY INSTALLATION FOR SHORT-TIME
EXPOSURES

Alfred Kuntke, Eindhoven, Netherlands, assignor
to N. V. Philips' Gloeilampenfabrieken, Eindhoven, Netherlands

Application January 29, 1932, Serial No. 589,696
In the Netherlands February 14, 1931

24 Claims. (Cl. 250—34)

For taking radiographs with a very short exposure time, use may be made of an installation wherein the energy for the X-ray tube is taken from a condenser which has been charged to a 5 sufficiently high tension, and which has sufficient capacity to permit the taking of the radiograph by a single discharge through the X-ray tube. Such a condenser may be caused to discharge by switching on the current for heating 10 the cathode of the X-ray tube and by thus making the discharge circuit conductive.

It is, however, preferable to employ a device by which the discharge is prevented until the incandescent cathode has attained that temperature at which the emission of useful rays occurs. For this purpose it has already been suggested to include in the discharge circuit a spark gap adapted to break down at a predetermined voltage. Such a spark gap may be so constructed 20 that at an arbitrary instant it can be made conductive, for example, by movably mounting one of its electrodes.

The purpose of my invention is to improve such an installation and it relates to an X-ray installation provided with a condenser connected to a charging circuit and to a discharge circuit; the latter circuit including an X-ray tube. This installation is provided with a device for causing the condenser to discharge through the tube; 30 which device is connected to a second device for switching off the charging current of the condenser in such manner that the operation of the two devices is coordinated.

This construction overcomes the following 35 drawback which was inherent in the previously known installations of this kind: If the condenser was caused to discharge through the X-ray tube without the charging current being switched off, the possibility remained that the source of current—which served to charge the condenser and which usually consists of a transformer having a rectifier connected in series to it—commenced to supply current directly to the X-ray tube with the result that, instead of a charge of short duration of said tube, a charge was produced which subsisted as long as the charging current remained switched on.

The great disadvantage of the above is particularly apparent under those conditions where the picture has to be taken at a definite instant and where a repeated exposure is either impossible or is attended with great difficulties, for example, in making radiographs of the stomach 50 or of the intestines. With the installation ac-

cording to the invention the possibility of making such errors is reduced to a minimum.

The installation may be constructed in different ways. For example, I prefer to include in the discharge circuit of the condenser an electrically-actuated switch, in which case the exciting circuit of the switch may be so connected to the charging circuit that the same switch serves for the closing or the interrupting of both 10 circuits.

If the charging circuit comprises an incandescent cathode discharge tube, an electricaly-influenced member bringing about the actuation of the switch located in the discharge circuit (for example, a magnet coil or the heating 15 wire of a bimetallic strip) may be connected in parallel or in series with the said incandescent cathode. This member may act directly on the switch, but may also be an intermediate relay which in its turn closes or interrupts an auxiliary 20 circuit. For switching off the charging current in this case, a switch may be used which only interrupts the heating current of the cathode of the discharge tube, or again a switch may be used with the aid of which the supply voltage for the 25 charging circuit is switched off. In the latter case provision must be made that the incandescent cathode of the X-ray tube in the discharge circuit should not be extinguished at the same time.

The installation may, however, also be such, that after the exposure is taken the switching off of the incandescent cathode of the X-ray is also automatically insured. For this purpose the heating circuit of this cathode may comprise a switch 35 actuated by a time-delay relay whose exciting current flows through the switch which serves to switch off the charging current. The time-delay for the disconnection of the heating current of the X-ray tube cathode must be sufficient 40 to permit the discharge of the condenser to take place.

In order that the invention may be clearly understood and readily carried into effect, it will be more fully explained with reference to the 45 accompanying drawings which represent, by way of example, some embodiments thereof, and in which:

Figure 1 is a schematic diagram showing the circuit arrangement of an installation in which 50 the charging circuit and the discharge circuit are switched on and off by closing or breaking the heating circuit of the cathodes of the rectifier tube and of the X-ray tube;

Figure 2 is a schematic diagram showing a 55

circuit arrangement of an installation comprising a relay; and

5 Figures 3 and 4 are schematic diagrams showing similar installations in which the exciting circuit of the relay is connected to the heating current circuit of a discharge tube included in the charging circuit.

In Figure 1, a condenser 1 is charged through a rectifying tube 3 from the secondary winding 10 of a transformer 2, whose primary winding is connected by conductors 4 to an alternating current network; a resistance 11 being placed in one of the conductors 4. The installation further comprises transformers 5 and 6, whose primary windings are also connected to the alternating current network, and whose secondary windings supply the heating currents for the incandescent cathodes of the rectifying tube 3 and of the X-ray tube 7 respectively.

20 One end of the primary windings of transformers 5 and 6 is directly connected to one of the conductors 4; the other ends of these windings lead to contacts 8 and 9, respectively, of a switch 10. If the switch 10 is placed on the contact 8, the transformer 5 is switched on and the incandescent cathode of the rectifying tube 3 is heated. This causes the transformer 2 to supply rectified alternating current to the condenser 1, which, therefore, some time after the current has been switched on, is charged up to the maximum value of the available tension. The resistance 11 limits the current and also determines the time of charge.

25 In order to cause the condenser to discharge via the X-ray tube 7, the switch 10 is placed on the contact 9 so that current is allowed to flow through the contact 9 to the transformer 6, thus bringing the cathode of the X-ray tube 7 to incandescence. At the same time, however, the 30 incandescent cathode of the rectifying tube 3 is deenergized so that the charging current circuit is blocked. Thereby a direct supply of energy by the transformer 2 to the X-ray tube 7 is precluded. Due to the X-ray tube 7 becoming conductive as a result of the heating of its cathode, a heavy discharge current is produced in the circuit formed by the condenser 1, a self-inductance 12 and the X-ray tube 7. This current generates in the X-ray tube 7 an intense radiation of X-ray 35 light which lasts only a short time, this time depending on the electrical constants of the circuit.

40 Figure 2, in which similar parts are denoted by the same reference numerals, merely differs from the installation of Fig. 1 in that the heating current for the incandescent cathode of the X-ray tube is supplied by a separate transformer 13 and not by the transformer 2, and that the transformer 6 serves for the excitation of a relay 14. With the aid of the relay 14, the discharge circuit 45 of the condenser 1 may be closed after the incandescent cathode of the X-ray tube has already attained its temperature. The relay 14 is constructed as a normally open relay, that is to say it closes its armature contact when the exciting current is switched on. If, as soon as the condenser 1 is charged, the switch 10 is placed on the contact 9, the charging current is switched off, the cathode of tube 7 is heated up, and the relay 14, being energized shortly thereafter, closes the 50 discharge current.

45 In the installation shown in Figure 3 use is made of an electromagnetic, normally-closed relay 15, i. e., a relay which makes contact with the interruption of its energizing current. The magnetic 55 net winding of this relay is connected in series

with the incandescent cathode of the rectifier 3 and is fed, together with the latter, by means of the transformer 16. A switch 17 is provided for switching on the primary current of transformer 16. If switch 17 is brought into the position shown, the incandescent cathode of the rectifier tube 3 is extinguished and as a result the charging current circuit is blocked. At the same time, however, the relay 15 is deenergized, which establishes the path for the discharging current.

50 The heating circuit of the cathode of the X-ray tube 7 is shown in this case to be independent of the switch 17; the primary of the heating transformer 13 being connected directly to the supply conductors 4.

55 The relay 15 may consist of a spark gap in which one of the electrodes is movable and in which, due to such deenergization of the relay coil, the mutual distance between the spark gap electrodes is decreased in such manner that a breakdown of the gap may occur. A very effective form of construction of such a relay is diagrammatically shown in the drawings as consisting of two vertically-aligned spherical bodies 18 and 19. Within the body 19 is arranged the magnet winding of a relay whose armature consists of a pin located behind an aperture in the wall of the body 19 and held fast by the magnetic force of the energized relay. If the exciting current of the relay is switched off, this pin drops 30 to protrude through the aperture to the outside. The strong concentration of the electric field between the electrodes 18 and 19, which concentration is due to the pointed shape of the armature, causes the instantaneous breakdown of the 35 spark gap.

60 Instead of being spherical bodies the electrodes of the spark gap may have otherwise shaped surfaces which permit the application of a great potential difference for a relatively small inter-electrode distance.

65 Discharge of the condenser 1 may also be caused with the aid of a switch included in the primary circuit of the transformer 2; such a switch being denoted by 20 in Figure 4. The 70 installation shown in Fig. 4 also comprises a time-delay relay 21, the exciting current of which likewise flows through the switch 20; the relay 21 keeping its contacts closed when the switch 20 is closed. The contacts of relay 21 are located in the primary circuit of the heating current transformer 13 whose circuit, however, is not controlled by the switch 20. When the switch 20, after having been closed, is reopened, the primary windings of the transformers 2 and 16, and 75 therefore also the exciting circuits of the relays 15 and 21, become deenergized. The relay 15 immediately closes the discharge circuit, but the relay 21, due to its time delay, does not switch off the heating current of the cathode of the X-ray tube 7 at the same instant, but only after the radiograph has been made. In the form of construction in Figure 4, the installation can consequently be operated by means of the switch 20 without any further auxiliary means. It is obvious that, if desired, one or more intermediate relay-circuits may be employed without departing from the principle referred to above.

80 In addition, Figure 4 comprises a resistance 22 through which flows the charging current of the condenser 1. In parallel with resistance 22 is connected a glow-discharge tube 23. This construction, which may also be employed in the other forms of construction of the installation according to the invention, serves to indicate the 85

moment at which the condenser 1 has taken up a sufficiently high charge to make the radiograph. The charging current produces across the ends of the resistance 22 a potential difference owing to which the glow-discharge tube 23 is ignited and emits light. The intensity of the charging current flowing through the circuit, and therefore the potential drop produced across the resistance 22, decreases with the increase of the tension on the condenser 1. If the condenser voltage has attained such a value that the voltage across the resistance 22 drops below a value sufficient to keep the glow-discharge tube 23 ignited, the extinguishing of this tube indicates that the condenser 1 has a sufficient charge and that the X-ray photograph can be made.

Fig. 4 also shows a condenser 24, connected in parallel to the glow-discharge tube 23 for the purpose of preventing the continuous alternating displacement currents flowing in the charging circuit from influencing the ignition of the glow-discharge tube. Such alternating displacement currents are caused by the fact that the anode and cathode of the rectifier 3 form a small condenser which is connected in series with the condenser 1, and the transformer 2. The transformer 2 applies an alternating voltage to these two series condensers, which causes—in addition to the charging current—a continuous alternating displacement current to flow through the circuit consisting of the transformer 2, resistance 22, condenser 1, and the condenser formed by the electrodes of the rectifier tube 3. This alternating displacement current continues after the direct charging current ceases to flow, and may be sufficiently large to cause in the resistance 22 a voltage drop in excess of the ignition voltage of the tube 23. This would cause the tube 23 to remain ignited and thus give an incorrect indication. To prevent this the condenser 24 is provided across the discharge tube 23; the capacity of the condenser relative to the other portion of the charging circuit being so large that the voltage drop across this condenser is smaller than the ignition voltage of the discharge tube 23.

What I claim is—

1. An X-ray installation comprising an X-ray tube, a high voltage condenser, a charging circuit for said condenser, a discharge circuit for said condenser including the X-ray tube, a contactor and a coil to close said contactor, and an energizing circuit for said coil, said coil when energized closing said contactor and establishing the discharge circuit, and means to control the flow of current in said charging circuit and in said energizing circuit, said means including a two-position switch which in one position prevents current flow in said charging circuit and permits current flow in said energizing circuit, and when in its other position permits current flow in said charging circuit and prevents current flow in said energizing circuit.

2. An X-ray installation comprising a high voltage condenser, a charging circuit and a discharge circuit therefor, a high voltage alternating current supply and a rectifying discharge tube having an incandescent cathode connected in said charging circuit, an X-ray tube having an anode and an incandescent cathode connected in said discharge circuit, said discharge circuit also comprising a movable switch member, electric actuating means to move said member, said electric actuating means when de-energized causing closure of said discharge circuit through said member, a common source for energizing the

cathode of the rectifier and said electric actuating means, and a switch to disconnect said source from said rectifier cathode and from said actuating means and thereby interrupt the flow of current in the charging circuit and establish the discharge circuit. 5

3. An X-ray installation comprising a high voltage transformer having output terminals, a high voltage condenser, an X-ray tube having an anode and an incandescent cathode, a rectifying discharge tube having an anode and an incandescent cathode, the anode of said rectifying discharge tube being connected to one output terminal of said transformer and the cathode of said X-ray tube being connected to the other output terminal of said transformer, said condenser being connected between said latter output terminal and the cathode of said rectifying discharge tube, an electrically energizable relay having a switch member, the cathode of said rectifier and the anode of said X-ray tube being interconnected by said switch member when the latter is closed, a second transformer to supply heating current to the cathode of the rectifier tube and to energize said relay, and a third transformer to supply heating current to the cathode of said X-ray tube, and a switch to de-energize said second transformer, and means including said switch to de-energize said third transformer after a given time interval. 30

4. An X-ray installation comprising a high voltage condenser, a charging circuit therefor comprising a rectifier tube having an incandescent cathode, a discharge circuit for said condenser comprising an X-ray tube having an anode and an incandescent cathode, a switch member in said discharge circuit and electromagnetic actuating means for said switch member, a common source to energize the cathode of the rectifier tube and said switch actuating means, and an interrupter to disconnect said source from said rectifier cathode and switch actuating means and thereby cause interruption of the flow of current in the charging circuit and establishment of the discharge circuit. 40

5. An X-ray installation comprising a high voltage condenser, a charging circuit therefor, a rectifier tube having an incandescent cathode in said charging circuit, a discharge circuit for said condenser, an X-ray tube having an incandescent cathode and an anode, and a switch member in said discharge circuit, electrical actuating means for said switch member, a common source to energize the cathode of the rectifier tube and said switch actuating means, an interrupter to disconnect said source simultaneously from the cathode of the rectifier and said actuating means and to thereby cause interruption of the charging circuit and establishment of the discharge circuit, and a separate circuit for heating the cathode of the X-ray tube, said circuit remaining energized after the interruption of the charging circuit. 50

6. An X-ray installation comprising a high voltage condenser and a charging circuit therefor, a rectifier tube having an incandescent cathode and a source of supply of high voltage in said charging circuit, a discharge circuit, an X-ray tube having an incandescent cathode and a movable member in said discharge circuit, means for electrically retaining said movable member in open-circuit position, a heating circuit for the incandescent cathode of the X-ray tube, and a common circuit for the heating of the incandescent cathode of the rectifier and for energizing 70

the means for electrically retaining said member, a time delay means to control the heating circuit of the X-ray tube, a switch member adapted to control said common circuit, said switch member when closed causing energization of the incandescent cathode of the rectifier tube and of the retaining means for said movable member, and also causes connection of the source of supply for the charging of the condenser, said switch member when open preventing the charge of the condenser and establishing the discharge circuit of the condenser, said time delay means maintaining the energizing circuit of the cathode of the X-ray tube for a given time interval after the opening of said switch.

7. An X-ray installation comprising an X-ray tube, a high voltage condenser, a charging circuit for said condenser and a second circuit to discharge said condenser through the X-ray tube, and means to indicate that the condenser is charging and the moment at which it is charged to a predetermined value, said means comprising a resistor disposed in the charging circuit and a glow-discharge tube connected across said resistor, the ignition voltage of said tube being lower than the voltage drop in said resistor when the condenser has been charged to the desired value.

8. An X-ray installation comprising an X-ray tube, a high voltage condenser, a charging circuit and a discharge circuit for said condenser, means to indicate the extent of charge of said condenser, said means including a resistor connected in said charging circuit, a glow discharge indicator tube, a second condenser, said indicator tube and second condenser being each in multiple with said resistor, the ignition voltage of said indicator tube being smaller than the voltage drop in the resistor while the condenser is being charged and the capacity of the second condenser being sufficiently large that the voltage drop across this condenser caused by the alternating displacement current is below the ignition voltage of the indicator tube when the first condenser is fully charged.

9. An X-ray installation comprising an X-ray tube, a high-voltage condenser, means including a switch and circuit for charging said condenser, a discharge circuit for said condenser including said X-ray tube, a contactor and a coil to close said contactor, and means for energizing said coil comprising an auxiliary circuit including said switch, said coil when energized closing said contactor and establishing the discharge circuit, said switch being adapted to assume two positions, in one of which positions it prevents current flow in the condenser charging circuit and closes said auxiliary circuit to cause the energization of said coil.

10. An X-ray installation comprising an X-ray tube, a high-voltage condenser, a charging circuit and a discharge circuit for said condenser, a source of high voltage in said charging circuit, said discharge circuit including said X-ray tube, and means to control the flow of current in said circuits and including a two-position switching device, said means preventing the flow of current in said charging circuit when said device is moved from one position and preventing the flow of current in said discharge circuit when said device is moved from its second position into said first position.

11. An X-ray installation comprising a high voltage condenser, a charging circuit for said condenser including a high-voltage supply source,

and an incandescent cathode rectifier tube, a discharge circuit for said condenser including an X-ray tube having an incandescent cathode and a movable member which in one position interrupts said discharge circuit, means to electrically retain said member in open circuit position, a common circuit for energizing the rectifier tube cathode and said electrical retaining means, a heating current supply transformer having a secondary winding in said common circuit and a primary 10 winding, a supply circuit including said primary winding and a switch member, a heating circuit for the X-ray tube cathode, a second heating current transformer having a secondary winding in said heating circuit and a primary 15 winding having supply leads, and a time lag relay in one of said latter supply leads and having an energizing coil connected in parallel with the primary winding of said first heating current transformer, said relay being opened at a pre-determined time after the deenergization of said coil.

12. An X-ray installation comprising an X-ray tube having an incandescent cathode, an alternating current supply, a high-voltage condenser 25 and a charging circuit therefor including a rectifier tube having an incandescent cathode, a discharge circuit for said condenser comprising said X-ray tube and a high-tension switch member adapted to establish the discharge circuit, means 30 for heating the cathode of said X-ray tube comprising an auxiliary circuit directly connected to said current supply, a time delay switch for controlling said auxiliary circuit and having electric actuating means which when energized cause 35 the switch to interrupt said auxiliary circuit after a predetermined time interval, a network current circuit for energizing the cathode of said rectifier tube and said high-tension switch member, said actuating means being electrically connected to 40 and energized from said network circuit, and a switch in said network circuit to interrupt the energization of said rectifier tube cathode, of said high-tension switch, and of said actuating means.

13. In an X-ray system for taking X-ray photographs in a short interval of time, the combination with an energy storage means connected to a source of rectified alternating current energy for accumulating an electrical charge in said energy storage means, and an X-ray tube connected to said energy storage means and adapted to be energized by the energy accumulated therein, of means connected to said energy storage means and said X-ray tube and operable to control the energization of the latter, and means 50 associated with said last mentioned means and said source of energy and operable to render said last mentioned means effective to cause energization of said X-ray tube by the accumulated charge, and to interrupt the accumulation of a 55 charge in said energy storage means from said source prior to rendering said last mentioned means effective to prevent said rectified alternating current source from imposing a sinusoidal wave upon the X-ray tube excitation energy. 60

14. In an X-ray system for taking X-ray photographs in a short interval of time, the combination with an energy storage means connected to a source of pulsating electrical energy for accumulating a charge in said energy storage 70 means, and an X-ray tube connected to said energy storage means and adapted to be energized by the energy accumulated therein, of means connected to said X-ray tube and said energy storage means operable to absolutely prevent any of 75

- the energy being supplied to said X-ray tube during the accumulation of said charge and operable to cause the accumulated charge to be instantaneously supplied to said X-ray tube, and means associated with said last mentioned means and said source of pulsating energy and operable to render said last mentioned means effective to cause said charge to be supplied to said X-ray tube, and to interrupt the accumulation of said charge from said source prior to rendering said last mentioned means effective whereby a sinusoidal wave form from the pulsating source is prohibited from being imposed upon the X-ray tube excitation energy.
15. In an X-ray system for taking X-ray photographs in a short interval of time, the combination with an energy storage means connected to a source of pulsating electrical energy for accumulating a charge of a predetermined maximum value, and an X-ray tube connected to said energy storage means and adapted to be energized by the charge accumulated therein, of means connected to said energy storage means and said X-ray tube, means connected to said second mentioned means and operable to cause the same to absolutely prevent any of the accumulated charge from being supplied to said X-ray tube until it has attained its predetermined maximum value, and operable to cause said second mentioned means to become ineffective and the accumulated charge to be initially supplied at its predetermined maximum value to said X-ray tube, and means associated with said last mentioned means and with said pulsating source for rendering said last mentioned means effective to cause energization of said X-ray tube and operable to cause a cessation in the accumulation of a charge in said energy storage means after the same has attained its maximum value and prior to rendering said last mentioned means effective, to prevent said pulsating source from imposing a sinusoidal wave form upon the X-ray tube excitation energy.
16. In an X-ray system for taking X-ray photographs in a short interval of time, the combination with an energy storage means for accumulating a charge from a source of rectified alternating current energy, and an X-ray tube adapted to be energized upon release of said charge from said energy storage means, of means connected to said energy storage means and said X-ray tube and operable to prevent any excitation of said X-ray tube during the accumulation of said charge and for causing release of said charge to said X-ray tube, and means operable to cause said last mentioned means to release said charge to said X-ray tube and to interrupt said rectified alternating current source prior to the release of said charge in order to prevent the imposition of a sinusoidal wave form from the alternating current source upon the X-ray tube excitation energy.
17. In an X-ray system for taking X-ray photographs in a short interval of time, the combination with an energy storage device connected to a source of pulsating electrical energy for accumulating a charge, and an X-ray tube connected to said energy storage device and adapted to be energized by the charge accumulated there-in, of a switching device connected to said X-ray tube and said energy storage device for controlling the energization of said X-ray tube, and means associated with said switching device and operable to render the latter operative to cause energization of said X-ray tube by the accumu-

lated charge, and to interrupt the accumulation of a charge in said energy storage device prior to rendering said switching device operative to cause energization of said X-ray tube, in order to prevent said pulsating source from imposing a sinusoidal wave form upon the X-ray tube excitation energy.

18. In an X-ray system for taking X-ray photographs in a short interval of time, the combination with an energy storage means connected to a source of rectified alternating current energy for accumulating an electrical charge in said energy storage means, and an X-ray tube connected to said energy storage means and adapted to be energized by the charge accumulated therein, of means connected to said energy storage means and to said X-ray tube and operable to control the energization of the latter, and means associated with said last mentioned means and said source of energy and operable to render said last mentioned means effective to cause energization of said X-ray tube by the accumulated charge, and to interrupt the accumulation of a charge in said energy storage means to prevent said rectified alternating current source from imposing a sinusoidal wave form upon the X-ray tube excitation energy.

19. In an X-ray system for taking X-ray photographs in a short interval of time, the combination with an energy storage means connected to a source of rectified alternating current energy for accumulating an electrical charge in said energy storage means, and an X-ray tube connected to said energy storage means and adapted to be energized by the charge accumulated therein, of means connected to said energy storage means and said X-ray tube operable to absolutely prevent any of the energy being supplied to said X-ray tube during the accumulation of said charge and operable to cause the accumulated charge to be instantaneously supplied to said X-ray tube, and means associated with said last mentioned means and said rectified alternating current source and operable to render said last mentioned means effective to cause energization of said X-ray tube by said accumulated charge, and to interrupt the accumulation of a charge in said energy storage means to prevent said rectified alternating current source from imposing a sinusoidal wave form upon the X-ray tube excitation energy.

20. In an X-ray system for taking X-ray photographs in a short interval of time, the combination with an energy storage means connected to a source of rectified alternating current energy for accumulating an electrical charge in said energy storage means, and an X-ray tube connected to said energy storage means and adapted to be energized by the charge accumulated therein, of means connected to said energy storage means and said X-ray tube operable to absolutely prevent any of the energy being supplied to said X-ray tube during the accumulation of said charge and operable to cause the accumulated charge to be instantaneously supplied to said X-ray tube, and means associated with said last mentioned means and said rectified alternating current source and operable to render said last mentioned means effective to cause energization of said X-ray tube by said accumulated charge, and to interrupt the accumulation of a charge in said energy storage means to prevent said rectified alternating current source from imposing a sinusoidal wave form upon the X-ray tube excitation energy.

21. In an X-ray system for taking X-ray photographs in a short interval of time, the combination of an energy storage means, a source of rectified alternating current energy connected to said energy storage means for accumulating an electrical charge therein, an X-ray tube connected to said energy storage means and adapted to be energized by the energy accumulated therein, means connected to said energy storage means and said X-ray tube and operable to control the energization of the latter, means associated with said second mentioned means and operable to render said second mentioned means effective to cause energization of said X-ray tube by the accumulated charge, and means associated with said source of rectified alternating current and operable to interrupt the accumulation of a charge in said energy storage means from said source prior to the operation of said last mentioned means to prevent said rectified alternating current source from imposing a sinusoidal wave upon the X-ray tube excitation energy.

22. In an X-ray system for taking X-ray photographs in a short interval of time, the combination of an energy storage means, a source of rectified alternating current energy connected to said energy storage means for accumulating an electrical charge in said energy storage means, an X-ray tube connected to said energy storage means and adapted to be energized by the charge accumulated therein, means connected to said energy storage means and to said X-ray tube and operable to prevent excitation of said X-ray tube during the accumulation of said charge and for causing release of said charge to said X-ray tube, means operable to cause said second mentioned means to release said charge with attendant energization of said X-ray tube, and means associated with said source of rectified alternating current and operable to interrupt the latter prior to release of said charge in order to prevent the im-

position of a sinusoidal wave form from the alternating current source upon the X-ray tube excitation energy.

23. An X-ray installation comprising an X-ray tube, a high-voltage condenser, a high-voltage transformer, a rectifying discharge tube having an incandescent cathode, an output circuit for said transformer including said condenser and rectifying discharge tube, a heating circuit for said incandescent cathode, a discharge circuit including said condenser and said X-ray tube, and means associated with said discharge circuit and said heating circuit and operable to control the flow of current in said circuits and including a two-position switching device, said means causing the energization of said heating circuit when said device assumes one of its positions and causing the deenergization of said heating circuit and permitting the flow of current in said discharge circuit when said device is moved into its other position.

24. An X-ray installation comprising an X-ray tube, a high-voltage condenser, a charging circuit for said condenser comprising a high-voltage transformer for supplying charging current to the condenser, a discharge circuit for said condenser including said X-ray tube, a movable member adapted to assume two positions and when in one position establishing said discharge circuit, electric actuating means to move said member from one position to another position, and means including a two-position switching device for controlling said charging circuit and said electric actuating means, said device when moved into one position causing the flow of current in said charging circuit and when moved to its other position causing the interruption of the flow of current in the charging circuit and the establishment of the discharge circuit.

ALFRED KUNTKE.
